Primary Examiner — Deanna L Pratt*Assistant Examiner* — Lilyana Bekic(74) *Attorney, Agent, or Firm* — Nixon & Vanderhye, P.C.(57) **CLAIM**

The ornamental design for a cuff for air delivery conduit, as shown and described.

DESCRIPTION

FIG. 1 is a perspective view of a cuff for air delivery conduit; FIG. 2 is a front view thereof; and,

FIG. 3 is a cross-sectional view thereof taken through the FIG. 3–FIG. 3 line of FIG. 2.

The broken lines show environmental structure of the conduit and the cuff for air delivery conduit. The broken lines do not form a part of the claimed design.
